UNITED STATES PATENT OFFICE.

EMIL SALTZKORN AND LUDWIG NICOLAI, OF DRESDEN, GERMANY.

APPARATUS FOR MANUFACTURE OF CARDBOARD BOXES.

SPECIFICATION forming part of Letters Patent No. 542,660, dated July 16, 1895.

Application filed February 27, 1893. Serial No. 463,852. (No model.) Patented in England February 7, 1893, No. 2,741; in Germany February 8, 1893, No. 70,479; in Belgium February 14, 1893, No. 103,434; in France February 14, 1893, No. 227,898, and in Austria-Hungary July 24, 1893, No. 8,785 and No. 24,570.

To all whom it may concern:

Be it known that we, EMIL SALTZKORN and LUDWIG NICOLAI, subjects of the King of Saxony, residing at Dresden, Saxony, in the Empire of Germany, have invented certain new and useful Improvements in Apparatus for the Manufacture of Cardboard Boxes and the Like, (for which we have obtained Letters Patent as follows: in Great Britain, No. 2,741, dated February 7, 1893; in Germany, No. 70,479, dated February 8, 1893; in Belgium, No. 103,434, dated February 14, 1893; in France, No. 227,898, dated February 14, 1893, and in Austria-Hungary, No. 8,785 and No. 24,570, dated July 24, 1893,) of which the following is a full, clear, and exact description.

The object of our invention is to provide a machine or apparatus to be employed in the manufacture of paper boxes, as more fully set forth hereinafter, reference being had to the accompanying drawings, in which—

Figure 1 is a front elevation partially in section on the line 1 1, Fig. 2, of a machine constructed in accordance with our invention. Fig. 2 is a transverse section of the same on the line 2 2, Fig. 1. Fig. 3 is a plan view of the same. Fig. 4 is a sectional elevation on the line 4 4, Fig. 5, of the strip-cutting device. Fig. 5 is a sectional elevation of the same on the line 5 5, Fig. 4. Fig. 6 is a detached perspective view of the guide-box into which the formed boxes are forced. Fig. 7 is a perspective view of a detail of construction, and Figs. 8 and 9 show the application of a scored or grooved blank to a former.

The various working parts of the machine are supported upon a suitable framework *a b c*, the upper portion *c* of which is provided with suitable bearings for the reception of a shaft *d*, connected at its upper end by a swiveled shackle *d'* to a chain *g* passing over a guiding-roller *F*, and having its opposite end secured to and adapted to be wound upon a winding-drum *v*. Near its lower end the shaft *d* is provided with a handle *h*, and at its lower end is secured a frame or former *i*, the latter being secured to the shaft *d* and capable of being readily removed for the substitution of a former or frame of different size, ac-

cording to the size or contour of the boxes to be manufactured.

The boxes which are to be manufactured are made from blanks previously cut and shaped to the desired size, and the machine is designed to hold the blank when bent up into the form of a box by means of a strip of pasted paper either on the inside or upon the outside of the box, and when it is desired to employ an inner lining-piece for holding the sides and ends of the box in position paper is fed to the former with its pasted side outward, and while its end is held in position against the former the latter is turned by means of the operating-wheel *h*, so that the band or strip entirely envelops it. After thus covering the former with the strip, that section of the latter to be employed is severed from the remainder by means of a separate cutting device *K*, and the blank *x* is placed in the position shown in Fig. 8, and its sides and end portions are turned up so as to come into contact with the pasted strip in the manner shown in Fig. 9. So far as this operation is concerned the box is practically complete, and it only remains to be delivered from the former and dried or it may be desired to cover the outside with a strip of similar material. In such case, or where it is desired to employ simply an outer covering for the blank, the former employed may be an ordinary block. In the operation of the machine when arranged for this purpose the previously-prepared blank is first held to the bottom of the former, as in Fig. 8. One of the sides of the cardboard is turned up against the former and the strip is pasted against it. Then the wheel *h* is turned with one hand while the other acts to turn up the three remaining sides of the blank, one after another, and then the pasted strip is drawn gradually around the box and cut off by the shears *K*. The holding device is then pushed aside and the formed box is discharged in the manner hereinafter described.

The frame *b* serves to carry four rolls *p* so disposed as to bear upon the four sides of the box as the latter is forced down between them by the former *i*, and acts to firmly press the

strip or sheets of cardboard upon the paste-covered strip and more firmly unite the two.

The lower portion *a* of the supporting-frame serves to support a series of vertically-arranged angular strips *r*, which, when placed in position, form a vertical guide-box of a shape corresponding to that of the box being manufactured, as shown more clearly in Fig. 6. The various strips *r* are held together by

- 10 transverse guiding-bolts *r'* extending through lugs *r²* on the various strips, and between the heads of the bolts and the lugs *r²* are coiled springs *r³* normally tending to force the strips toward each other and press the pieces of
- 15 cardboard upon the strip of pasted paper, the tension of the spring being adjusted by screws *r⁴*. The central portion of each of the sides of the box or guide is open to permit the free circulation of air to assist in drying the paste,
- 20 and at their upper edges are spring-held fingers *s* having upper beveled edges, which, as the former *i* is depressed, are forced outwardly by the lower edge of the former, and after the upper edges of the box have passed
- 25 below the fingers the latter are again moved in by their springs and act as strippers to remove the formed box from the former *i*. The box or guide is of sufficient length to contain a number of boxes so that between its entrance to the guide and its final discharge sufficient time will have elapsed to permit the thorough drying of the paste.

Adapted to a guiding-platform *x'* at the base of the machine is a delivery-box *y*, from the opposite side of which extend arms *y'* secured at their outer ends to chains *w²* passing over guiding-pulleys *w³* and carrying at their free ends counterbalance-weights *w⁴*, which normally tend to retain the delivery-box in position immediately beneath the discharge-mouth of the guide *r*. The rear end of the delivery-box is secured to chains *w'*, which extend to drums *v²* secured to the shaft *t* and passing partly around said drums in the same direction as that in which the chain *g* passes around the drum *v*. The shaft *t* is also provided with a drum *v'*, from which extends a chain *w* to a pedal *Z*, so arranged with respect to the various drums *v v²* that on the depression of the pedal the shaft and all its drums will be revolved, causing the chain *g* to be partially wound upon its drum *v'* and raising the shaft *d* and the former *i* to the position illustrated in Fig. 2, while the chains *w* are also partially wound upon their drums *v²* and the delivery-box *y* is moved from its normal position beneath the guide *r*, as shown by dotted lines in Fig. 2, a slight distance to the rear, as shown by full lines in said figure, and delivering one or more of the formed boxes. Upon the release of this pedal the counterbalance-weights *w⁴*, acting upon the chains *w²*, will again draw the delivery-box back to its normal position, and the weight of the former *i* and its shaft *d* will cause the latter to descend and force the completed box between the squeezing-rollers *p* and into the guide *r*.

The proper position of the former *i* with respect to the squeezing-rollers and the guide is determined by the guiding-plates *c'*, carried at the upper portion of the frame *c*, and to which is adapted a guiding-pin *c²*, which, during the turning of the shaft and former, is normally above the mouth of such guides, the latter being gradually inclined toward each other, so that the pin *c²* will be caught by the guides as the shaft *d* descends, and before the entrance of the former *i* between the pressing-rolls the shaft will have been turned axially until the former assumes the proper position.

During the turning of the former and the placing of the blank against the paste-covered strip of paper or the covering of a blank by a pasted strip the former may be held up in the position shown in Fig. 2 by means of a locking-catch *u'*, adapted to extend over the treadle *Z*, and under the control of an operating-lever *u*, the catch being preferably acted upon by a spring *u²*, as shown in Fig. 7, so that it will automatically engage with the treadle each time the latter is depressed.

The mechanism for severing from the pasted strip a section of sufficient length for the completion of the box is more clearly illustrated in Figs. 4 and 5. This mechanism comprises a frame *k*, from which projects an arm *k'*, adjustably secured by a screw *k²* in a box *K*, depending from a stanchion *K²*, which latter is adapted to an orifice in a lug *k³* projecting from the frame *c*, the adjustment of the frame *k* being for the purpose of enabling the operator to adjust the position of the cutting-knives in accordance with the size and character of the box being manufactured. Pivoted centrally at *b³*, within the frame or casing *k*, are two arms *l*, one of which carries a cutting-knife *l'*, and to the opposite arm is secured a block *l²*, of wood, lead, or the like, so arranged as to form a cutting-base for the knife *l'*. The upper ends of the levers *l*, which project beyond the pivot-point, are connected by links *l⁴* to a rod or spindle *m*, guided within the upper portion of the frame *k* and connected at its upper end to a lever *M*, pivoted at *n'* to the stanchion *K²* and connected at its extreme outer end to a treadle *o* through the medium of a connecting-rod *o*, having a yielding or spring-like central section which will yield when the cutting-edge of the blade *l'* is tightly pressed against the block *l²*, and thus avoid injury to the blade. In order to normally keep the arms *l* apart in readiness for action, a tension-spring *m'* is located within an offset in frame *k* and is connected at one end to the frame and at the opposite end to the lever *M*, so as to normally depress the rod or spindle *m* and keep the arms *l* apart.

Having thus described our invention, what we claim, and desire to secure by Letters Patent, is—

1. The combination of the former, a shaft carrying the same, pressing rolls between

which such former is adapted to be passed, a guiding box comprising a series of angular strips, yielding connections between such strips, and stripping fingers provided at or about the upper end of said guide box, substantially as specified.

2. The combination of the former, an axially movable and rotatable shaft carrying the same, a laterally projecting guiding pin carried by such shaft, guideways carried by the frame and to which such pin is adapted, pressing rolls between which such former is adapted to pass and a guiding box located below said pressing rollers, substantially as specified.

15 3. The combination of the former, a shaft carrying the same, a guiding box having outwardly movable walls into which such former is adapted to be forced and laterally yielding stripping fingers carried by the movable walls at the upper end of such guide box, substantially as specified.

20 4. The combination of the former, a rotatable shaft carrying the same, devices for raising and lowering such shaft, a hand wheel secured to the shaft and bearings provided in the frame and in which said shaft is movable, substantially as specified.

25 5. The combination of the former, *i*, a rotatable shaft, *d*, carrying the same, means for effecting the raising and lowering of such shaft, hand wheels secured to said shaft, a supporting frame, bearings provided in the frame for the reception of said shaft, a guiding pin secured to the shaft and guideways provided on the frame and adapted to act upon the said guiding pin, substantially as specified.

30 6. The combination with the box forming mechanism, of the guide, *r*, a delivery box, *y*, located beneath such guide and adapted to be moved toward the rear of the machine each time a completed box is forced from the guide, *r*, into said delivery box substantially as specified.

45 7. The combination of the former a carrying shaft therefor, a chain, *g*, having one end secured to such former carrying shaft and at its opposite end secured to a drum, *v*, a shaft carrying said drum, drums, *v*², on such shaft, a delivery box or slide, *y*, chains, *w*', extending from said delivery box to the drums, *v*², an operating drum, *v*', secured to such shaft, a treadle, *Z*, and a chain, *w*, extending from

said treadle to the operating drum, substantially as specified.

55 8. The combination of the former a carrying shaft therefor, a chain, *g*, having one end secured to such former carrying shaft and at its opposite end secured to a drum, *v*, a shaft carrying said drum, drums, *v*², on said shaft, a delivery box or slide, *y*, chains, *w*', extending from said delivery box to the drums, *v*², counterbalance weights, *w*⁴, chains connecting such counterbalance weights to the delivery box, an operating drum, *v*', secured to the shaft, a treadle, *Z*, and a chain, *w*, extending from said treadle to the operating drum, substantially as specified.

9. In combination with the former and its operating devices, a guide box comprising a series of corner sections, *r*, lugs, *r*², formed on such sections, holding bolts, *r*', extending through such lugs and compression springs adapted to said bolts, substantially as specified.

75 10. A cutting device comprising a supporting frame, levers pivoted thereto and carrying at their free ends cutting mechanism, a spindle as *m*, guided by said frame, links as *l*', connecting said levers to the spindle, and a treadle operatively connected to said spindle, substantially as specified.

11. The combination of the frame, *k*, levers, *l*, pivoted thereto, a cutting blade, *l*', carried by one of said levers, a cutting block, *l*², carried by its fellow, a spindle as *m*, links, *l*', connecting the levers to said spindle, a pivoted lever, *M*, connected at one end to said spindle and at its opposite end being operatively connected to a treadle, substantially as specified.

85 12. The combination of the frame, *k*, levers, *l*, pivoted thereto, a cutting knife, *l*', carried by one of said levers, a cutting block, *l*², carried by its fellow, a spindle, *m*, links connecting said spindle to the levers, an operated lever as *M*, pivoted to said spindle and a spring extending from the fixed frame to the lever, *M*, and normally tending to separate the levers, *l*, substantially as specified.

90 In testimony thereof we have hereunto set our hands in the presence of two witnesses.
